ELECTRON DISCHARGE DEVICE

Frank Douglas Goodchild, London, England, assignor to Standard Telephones and Cables Limited, London, England, a British company

Application October 28, 1942, Serial No. 463,698
In Great Britain December 2, 1941

10 Claims. (Cl. 250—27.5)

This invention relates to electron discharge tubes and has for its main object to provide an improved construction of tube for high frequencies which can be connected directly into a transmission line and be utilised as a line oscillator. Triode tubes are known having two pairs of leads for the plate and grid emerging from opposite sides of the bulb so that the tube can be connected directly into a transmission line, but this type of construction is very difficult from the manufacturing standpoint, as considerable shrinkage is encountered due to cracked glass. Tungsten is the metal usually employed, sealed into hard glass.

According to the present invention, we utilise the disc seal principle and the tube comprises an envelope and a pair of metallic discs sealed through said envelope and connected respectively one to the anode and one to the grid, these discs extending outside the envelope of the tube to provide direct connections to the anode and grid, whereby they may be connected directly to an external circuit such as a transmission line, and assist in the dissipation of heat.

It is desirable to support the anode, which may be of molybdenum, so that its working part may attain a temperature considerably in excess of 1000° C. while still utilising the heat conducting properties of the copper supporting disc to get as much heat away as possible. If the copper disc is in immediate contact with the working part of the anode then the anode may not be allowed to exceed 1084° C. which is the melting point of copper: in fact it must not even approach the figure otherwise the copper will volatilise on to the bulb and form a poor insulation path between grid and anode.

According to a feature of the present invention the anode is attached to its supporting disc via a plurality of fins which are adapted to provide a temperature gradient between the working part of the anode and its supporting disc. With this arrangement it has been found to be possible to dissipate considerably more heat than was possible with the direct connection between anode and disc and at the same time removes any danger of copper depositing on the bulb.

According to another feature of the invention the connection between the grid and grid disc comprises a spider like member mounted on the grid leads and having a plurality of spring fingers adapted to make a wiping contact with the grid disc.

Features of the invention will be hereinafter described with reference to the accompanying

drawings and pointed out in the appended claims. In the drawings

Fig. 1 is a sectional elevation of a complete tube;

5 Fig. 2 is an exploded view thereof.

Fig. 3 is a sectional elevation of a modified construction of tube and

Fig. 4 is an exploded view thereof.

Sealed into the envelope 1 of the tube are two 10 metallic discs 2 and 3. In the construction shown in Figs. 1 and 2 the disc 2 is in the form of a funnel-shaped spinning, of which the funnel portion 4 supports the anode 5, which as shown, is of cylindrical form but obviously, for the purposes of this invention, it may have various forms of an elongated hollow body, together with a molybdenum annular disc 6 which is secured at its inner edge to the anode near the middle point where the anode is hottest and at its outer edge in the 20 base of the funnel by the punched-out lugs 7. Rods 8 are welded to the sides of the anode and to the molybdenum disc 6 for additional support.

The grid 9 and cathode 10, together with the heater leads, are mounted on the press 11 of the 25 tube, and attached to the grid supporting rods are two contact springs 12 which, when the press is assembled and sealed into the tube, make contact with the lower side of the metal disc 3 and form the electrical connection to the grid.

30 In the construction shown in Figs. 3 and 4 the tube comprises a glass envelope 1 having sealed into it the copper anode disc 2 and grid disc 3. The disc 2 has a central boss portion 4¹ to support the cylindrical anode 5 through the medium 35 of the radial fins 6¹ and collar 7¹. As shown the anode structure is built up of a plurality of molybdenum pressings each shaped to form an integral part of the cylindrical working part of the anode with its associated fins and collar portion, 40 the pressings being suitably secured together as by the slots and lugs 8¹ and 9¹ on the fins. The anode assembly is secured in the boss portion 4¹ of the disc 2 by bent over lugs 10¹ of the disc engaging the collar 7¹ the lower edge of the boss portion being provided with an inwardly directed retaining lip 11¹ to engage the collar. It will thus be seen that the working portion of the anode is separated from the disc 2 by the fins 6¹.

45 The grid 9 and cathode 10 are mounted on the press 11 to lie within the anode 5 and in order to provide a low impedance connection between the grid disc 3 and the grid 9 a spring spider member 12¹ is mounted on the grid support rods 13 and the spring arms of the spider make a wiping contact with the under surface of the grid

disc 3. As shown the grid support rods 13 are provided with glass arbors 14 which help to reduce losses between the grid and cathode supports by increasing the glass path between them. Alternatively a cross shaped press may be provided for this purpose.

It will be seen that with the construction of tube according to this invention transmission lines can be attached direct to the copper discs 2 and 3 giving connection to the anode and grid respectively. In addition, it has been found that the intimate connection of the copper with the glass greatly assists the dissipation of heat.

What is claimed is:

1. An electron discharge tube comprising an envelope, a metallic disc sealed through the wall of said envelope and supporting an elongated hollow anode with its length direction at right angles to the plane of the disc, a cathode and grid mounted on supports carried by one end portion of the tube and positioned within said anode, a second metallic disc sealed through the wall of the envelope and having a hole through which the grid and cathode supports extend, and means comprising spring contacts for making electrical connection between the grid and second disc.

2. An electron discharge tube comprising an envelope, an anode supported by a metallic disc sealed through said envelope and extending outside it providing a direct connection to the anode for assisting in the dissipation of heat, said anode being attached to the disc by a plurality of fins which are adapted to provide a temperature gradient between the working part of the anode and said disc.

3. An electron discharge tube comprising an envelope, an anode and a grid mounted on supports within the envelope and a pair of metallic discs sealed through said envelope and connected within the envelope respectively one to the anode and one to the grid said discs extending outside the envelope providing direct connections to the anode and grid for assisting in the dissipation of heat said grid being connected to its respective disc by means of a spring spider member mounted on the grid supports with its spring arms making wiping contact with the disc.

4. An electron discharge tube according to claim 1 wherein the anode comprises a working

part having a plurality of outwardly extending fins and a surrounding collar portion secured in a central boss in the anode disc.

5. An electron discharge tube according to claim 1 wherein the disc supporting the anode comprises a funnel-shaped portion integral with said disc and embracing the anode and an annular disc surrounding and attached to the anode and secured in the base of said funnel portion whereby the anode is supported at two points along its length.

6. An electron discharge tube according to claim 1, wherein the anode comprises a plurality of sheet metal parts secured together and forming an elongated hollow body having a plurality of outwardly extending fins, and a surrounding collar, each of said metal parts comprising a portion forming a working part of the anode, a fin forming part, and a circumferential collar forming part.

7. An electron discharge tube according to claim 1 wherein the disc supporting the anode comprises a funnel shaped portion integral with said disc and embracing the anode and an annular disc surrounding said anode and attached at its inner edge to said anode near the longitudinal center of this latter whereby the maximum cooling from contact with the disc is obtained, the said annular disc being secured at its outer edge in the base of said funnel.

8. An electron discharge tube according to claim 2 wherein the anode comprises a working part having a plurality of outwardly extending fins and a surrounding collar portion secured in a central boss in the anode disc.

9. An electron discharge tube according to claim 2 wherein the anode comprises a plurality of sheet metal parts secured together and forming an elongated hollow body having a plurality of outwardly extending fins, and a surrounding collar, each of said metal parts comprising a portion forming a working part of the anode, a fin forming part and a circumferential collar forming part.

10. An electron discharge tube according to claim 1 in which the contact springs are carried by the grid supports and make spring contact with the second disc.

FRANK DOUGLAS GOODCHILD.
